UNITED STATES PATENT OFFICE.

GEORGE DRYDEN, OF BOSTON, MASSACHUSETTS.

DEVICE FOR RENDERING A PULLEY TIGHT OR LOOSE UPON A SHAFT.

SPECIFICATION forming part of Letters Patent No. 252,036, dated January 10, 1882.

Application filed October 17, 1881. (No model.)

To all whom it may concern:

Be it known that I, GEORGE DRYDEN, of Boston, in the county of Suffolk and State of Massachusetts, have invented a new and useful improved device for rendering the same pulley practically tight or loose upon a shaft at will, of which the following is a specification.

My invention is principally of value in reversing elevating machinery for running elevators in buildings, and is shown in the drawings as applied to such elevating machinery; but it may be applied in place of the ordinary tight and loose pulleys whenever and wherever practicable.

My invention may be described as follows, reference being had to the accompanying drawings, which form a part of this specification.

Figure 1 of the drawings is a view in perspective of my invention as applied to elevating machinery. Fig. 2 is an elevation in part section, (several of the important portions of the invention being in section,) which section is cut on the line *x* of Fig. 3; and Fig. 3 presents a view in perspective of those leading features of the invention which are in section in Fig. 2.

Like letters of reference indicate like parts in the different figures of the drawings.

The invention consists in one upward pulley and one downward pulley placed loose upon the worm-shaft of an elevating-machine. Over the periphery of the hub of each of said pulleys is placed a spring, said spring being covered by a sleeve, which sleeve fits over and around said spring and is fast to the worm-shaft. The spring passes around over said hub and within said sleeve, the two ends of the spring passing through the sleeve and forming two lips, a lever-bar with a tapering slot at one end thereof, and with the pivot forming the fulcrum attached to the sleeve. A loose tapering sleeve with an annular slot at the center thereof is placed upon the worm-shaft. An eccentric is placed upon the "shipping-shaft," the eccentric-rod connecting, by means of an ordinary cross-head, with an oscillating lever, which lever is provided with a stud, said stud being placed in said annular slot, so that by pulling the shipping cord in the car, which cord is attached to the end of the shipping-shaft, the tapering grooved sleeve is moved to and fro on the worm-shaft, and as said sleeve

is passed under the end of the lever-bar opposite to the slotted end thereof, said opposite end being thereby raised, the tapering slot in the lever-bar is pressed down over the two lips of the spring, thereby pressing said lips together and tightening said spring around said pulley-hub, and thereby making the pulley tight, all to be constructed and operated in a manner to be hereinafter fully described.

A represents the worm-shaft of an elevating-machine. B is the upward belt-pulley, and B' the downward belt-pulley. The downward pulley is equipped in the same manner as is the upward pulley, in connection with which latter the invention is fully illustrated in the drawings. The hubs *b*² of the two pulleys B and B' are loose upon the worm-shaft. A spring, *e*, is fitted easily around the periphery of each pulley-hub, so that said hub can, when the device is in the position shown by the drawings, revolve within said spring. The two ends *c*² and *c*³ of the spring are carried up through the sleeve *b*, forming lips, as clearly shown in Fig. 3, said sleeve *b* fitting over the spring *e*, as shown. The sleeve *b*, however, is keyed fast to the worm-shaft A.

The lever-bar C passes between the lips *c*¹, which lips form a part of the sleeve *b*, and is held by the pivot *c*⁴, which pivot forms the fulcrum of said lever. In the lever C, and near the end thereof, is the slot *d*, which slot tapers as it passes inward, being smaller at the inside than at the outside end thereof, as shown in the drawings.

The sleeve D is loose upon the worm-shaft A, and tapers both ways from its center, as shown in Fig. 1. Said sleeve is provided with the annular slot *e*, said slot passing completely around said sleeve.

The eccentric H is placed upon the shipping-shaft J in the usual manner, and the eccentric-rod G is pivoted to the cross head *g* in the ordinary manner, as shown in Fig. 1. The oscillating lever F is also pivoted to the cross-head *g*, and is provided with a stud, *f*, which stud is inserted in the annular slot or groove *e*, all of which is shown in Fig. 1. The shipping-cord, which is controlled by the boy running the elevator-car, is attached to the shipping-shaft J at the end thereof in the usual manner.

Having described the construction of my new device and its application to elevating machin-

ery, I will describe its operation as follows: The drawings show the invention in what may be called its "normal position"—that is to say, it is shown in the position occupied when the elevator-car is not in motion and both the pulleys B and B' are running loose. It is now desired, for example, to move the car upward. The boy in charge pulls the shipping-cord and turns the shipping-shaft J so as to throw the eccentric H back. This, as is obvious from an examination of the drawings, moves the end of the oscillating lever F, which is inserted in the annular slot e by means of the stud f, in the opposite direction, running one end of the loose tapering sleeve D under the end of the lever C; and it is obvious that at the same time the opposite end of said lever is lowered, pressing the tapering slot d down over the lips c² and c³ of the spring e, thus pinching said lips more and more tightly together until the ends of the lips touch the inner end of the slot. The spring e is thus bound tightly around the periphery of the pulley-hub b²; and as the two lips c² and c³ are held in the sleeve b, and said sleeve b is keyed fast to the worm-shaft A, and the lever C is held between the lips c', which lips form a part of the sleeve b, it is readily seen that the pulley B is made practically tight upon the worm-shaft, and the worm-shaft is made to turn thereby, as said pulley is connected with the source of power by means of the belt M. When the car is to be run downward the shipping-cord is pulled so as to turn the shipping-shaft J in the opposite direction, carrying the eccentric H forward, thus throwing the cross-head g, and with it the oscillating lever F, forward, as shown by dotted lines in Fig. 1, and running the loose sleeve D under the end of the lever C', which lever corresponds with the opposite lever, C, before described. The downward pulley B' is made practically tight in the same manner, and the

worm-shaft A is turned so as to move the car downward.

It is hardly necessary to state that the 45 crossed belt N (seen in Fig. 1) is the downward belt.

Having thus described my invention and the manner of carrying the same into effect, what I claim as new, and desire to secure by Letters 50 Patent, is—

1. In an elevating-machine, the mode of rendering a pulley practically tight upon a shaft and in turn loosening the same by means of a spring carried around over the periphery of the 55 pulley-hub and inside of a sleeve, which sleeve is keyed fast upon said shaft, the two ends of said spring holding it firmly in and to said sleeve, said spring to be operated by a slotted lever-bar, the end of said lever-bar being raised 60 and lowered by a loose tapering slotted sleeve, said latter sleeve to be moved back and forth by means of an eccentric, and an oscillating lever forming the connection between the eccentric-rod of said eccentric and said loose annular slotted sleeve, substantially as described 65 and shown.

2. In combination, the pulleys B and B', with hubs b², the two corresponding springs e, with ends or lips c² and c³, the corresponding sleeves 70 b and b', with lips c', the corresponding levers C and C', with tapering slots d, the worm-shaft A, the tapering loose sleeve D, with annular slot e, the oscillating lever F, provided with the stud f, the cross-head g, the eccentric H, 75 with eccentric-rod G, and the shipping-shaft J, operated by the shipping-cord, all constructed and arranged substantially as described, and for the purpose set forth.

GEORGE DRYDEN.
